UNITED STATES PATENT OFFICE

98,030

DESIGN FOR A JAR

Charles L. Gaunt, Dunkirk, Ind., assignor to Bunte Brothers, Chicago, Ill., a corporation of Illinois

Application October 2, 1935, Serial No. 58,787

Term of patent 14 years

To all whom it may concern:

Be it known that I, Charles L. Gaunt, a citizen of the United States, residing at Dunkirk, in the county of Jay and State of Indiana, United States of America, have invented a new, original, and ornamental Design for a Jar, of which the following is a specification, reference being had to the accompanying drawings forming a part thereof.

The front and rear sides of the jar are identical in appearance.

I claim:

The ornamental design for a jar as shown and described.

CHARLES L. GAUNT.
